Primary Examiner — Amy C Wierenga(74) *Attorney, Agent, or Firm* — Stetina Brunda Garred and Brucker(57) **CLAIM**

The ornamental design for a piston seating device for a valve, as shown and described.

DESCRIPTION

FIG. 1 is a perspective view of a piston seating device for a valve;

FIG. 2 is a top view of FIG. 1;

FIG. 3 is a bottom view of FIG. 1;

FIG. 4 is a right-side view of FIG. 1; and,

FIG. 5 is a left-side view of FIG. 1.

The broken lines represent portions of a piston seating device for a valve that form no part of the design to be patented.
